UNITED STATES PATENT OFFICE

THOMAS J. LAVAN, OF CLEVELAND, OHIO

TRACK BALLASTING

Application filed October 18, 1927. Serial No. 226,916.

My invention relates to track ballasting.

At the present time it is quite usual to construct street railway tracks in paved streets by forming a trench, laying the track therein by the use of what are commonly known as twin ties, blocking the whole to raise the top of the rails to the level of the top of the pavement, and then pouring concrete into the trench usually to the level of the top of the bearing plates of the twin ties. In some cases the concrete flows under the twin ties sufficiently to form a base strong enough to withstand fairly well the loads imparted to it by the passage of rolling stock along the track, and in such cases the track stands up reasonably well; in other cases the concrete flows under the ties to such a lesser extent that the abutment is of an area entirely insufficient to withstand the loads so imparted to it, and in such case the track fails quickly. In any case the presence of any unfilled space beneath the bearing plates tends to hasten failure of the track installation not only because it reduces the area of the concrete abutment but also because it permits frost deterioration of the concrete bed by providing a pocket in which moisture may collect.

The principal object of my invention is to provide a method for forcing the concrete beneath these bearing plates, and means for carrying out this method, and in the drawings accompanying this specification, and forming a part of this application, I have shown, for purposes of illustration, one form which my invention may assume.

In these drawings:

Figure 1 is a view showing a track of the type above referred to constructed according to the embodiment of my invention herein disclosed, the four portions of the figure showing the track in four successive stages of construction,

Figures 2 through 5 are sections respectively on the lines 2-2, 3-3, 4-4, and 5-5, of Figure 1, Figures 3 and 4 showing also the means herein disclosed for carrying out the method of construction herein disclosed, while

Figure 6 is a plan view of this herein disclosed means.

According to the embodiment of my invention herein disclosed the trench 11 is formed, and the track is assembled therein by securing the rails 12 to the bearing plates 13 of twin ties 14 which comprise in addition to the bearing plates 13 cross ties 15 riveted to the bearing plates 13 and useful particularly to hold the bearing plates 13 properly spaced and assembled into a single unit, and the assembled track is then raised until the top of the rails 12 reach the level to be assumed by the pavement, and the track is blocked in this raised position, all in the usual manner, the track at this point in its construction being shown in plan in the top portion of Figure 1, and in section in Figure 2. Next the concrete 16 is poured into the trench 11 approximately to the level of the top of the bearing plates 13, again in the usual manner, the track at this point in its construction being shown in plan in the second portion of Figure 1, and in section in Figure 3. According to ordinary construction the concrete then is leveled off roughly, and hand tamping is relied upon to cause the concrete to flow beneath the bearing plates 13, and the difficulties herein above recited result; according to my invention the concrete is forced beneath the bearing plates 13 to entirely fill the space beneath the bearing plates 13 and between the bearing plates 13 and the under-bed formed by the bottom of the trench 11.

According to the embodiment of my invention herein shown this is accomplished by applying pressure to the concrete adjacent the bearing plates 13 on the two sides thereof over a considerable area on each side of the bearing plate 13 and in a direction to force the concrete to flow under the bearing plate 13 to completely fill the space beneath the bearing plate 13 and between the bearing plate 13 and the bottom of the trench 11, and this result is accomplished by the machine shown in elevation in Figures 3 and 4 and in plan in Figure 6.

This machine herein shown comprises a car 95 17 built upon two pair of longitudinal channels 18 extending the length of the car, supporting, in the two channels of each pair, axles 19 on which are mounted wheels 20 formed to ride upon the rails 12 of the track 100

being constructed, supporting, at their rear ends and adjacent their front ends, a pair of cross channels 21 serving to unite the longitudinal channels into a unitary frame and also 5 to support a car platform 22, and supporting, at their front ends in advance of the front cross channel 21, a pair of mechanism supporting cross channels 23 and 24.

Depending from the channels 23 and 24 are 10 four pair of supporting plates 25, and mounted in each pair of supporting plates 25 is a double-acting pneumatic cylinder 26 having a connection 27 leading to the chamber ahead of the piston head having a connection 28 leading 15 to the chamber in rear of the piston head, and carrying on its piston head a piston rod 29 to the outer end of which is secured a head 30. The cylinders 26 are so located, and are disposed at such an angle, that projection of 20 the piston rods 29 will cause the heads 30 to engage the ballast on the two sides of the two bearing plates 13 and force the concrete beneath the bearing plates 13 into the spaces between the bearing plates 13 and the bottom of 25 the trench 11, and compact the concrete in these spaces, thus to fill these spaces tightly with compacted concrete.

Operation of the heads 30 in unison is effected by a single control valve 31 to which 30 is connected a duct 32 leading from a source of compressed air (not shown), a duct 33 leading to the cylinder connections 27, and a duct 34 leading to the cylinder connections 28, the valve 31 being of a usual construction by 35 which in one position the duct 33 is opened to atmosphere and the duct 34 connected to the supply duct 32 to supply air rearwardly of the piston heads and advance the piston rods 29 and heads 30 from the retracted position 40 shown in Figures 3 and 6 to the advanced position shown in Figure 4, and by which in the other position the duct 34 is opened to atmosphere and the duct 33 connected to the supply duct 32 to effect the reverse movement.

45 From a consideration of the above description it will be obvious to those skilled in the art that when this machine, with the heads 30 retracted, is moved into position with the heads 30 above the bearing plates 13 of a twin tie about which the concrete has been poured but under the bearing plates of which the concrete has not yet been compressed, all as shown in plan for the track in the second portion of Figure 1 and for the machine in Figure 6, and 50 in elevation in Figure 3, then actuation of the cylinders 26 will cause the piston rods 29 and heads 30 to advance somewhat downwardly but generally laterally to force the concrete under the bearing plates 13 until the 55 entire space beneath the bearing plates 13, and between the bearing plates 13 and the bottom of the trench 11, has been tightly filled with compacted concrete, and the track has reached that stage of construction shown in plan in 60 the third portion of Figure 1 and in eleva-

tion in Figure 4, and the machine has reached the position shown in elevation in Figure 4, also that reverse actuation of the cylinders 26 will withdraw the piston rods 29 and heads 30 into the retracted position of Figures 3 and 6 70 to permit the car 17 to be advanced into position ready for the succeeding operation of the machine, the depressions made by the heads 30 laterally of the bearing plates 13 preferably being filled in any suitable manner, as by 75 introducing by hand the excess concrete usually piled up intermediate the rails 12.

While my invention does not contemplate any exact dimensions for the heads 30 it will be obvious to those skilled in the art that the angle and movement of the heads 30 must be so proportioned that the heads 30, acting on the concrete in the manner in which it is being deposited, will intercept and carry forward an amount of concrete sufficient to tightly fill 80 with compacted concrete the spaces beneath the bearing plates 13 and between the bearing plates 13 and the bottom of the trench 11, and accordingly it will be understood that the angle and movement of the heads 30 must be 85 coordinated, and that the manner of depositing the concrete in the trench must be correlated with the result of the coordination of the angle and movement of the heads 30. Obviously the heads 30 can be made of any width 90 sufficient to cause the force imparted by the heads to continue as a thrust forcing the concrete under the bearing plates 13 rather than as a wedge moving the concrete aside longitudinally of the track, but where a machine is 95 to be used regularly in connection with twin tie track construction it of course will be advantageous to form the heads of the same width as the space between the cross ties of the twin ties, so that each operation of the 100 machine will fill the entire spaces under the two bearing plates of the twin tie being operated on thus permitting the machine to be moved an entire twin tie spacing between each 105 operation and the operation next succeeding.

110 It of course will be obvious to those skilled in the art that my invention may be applied to constructions other than those embodying twin ties set in concrete ballast, and that both the method and means of my invention may be variously changed and altered from the method and means herein specifically disclosed, both with the type of track construction herein specifically considered and also to adapt my invention to other types of track 115 construction to which it may be applicable, all without departing from the spirit of my invention or sacrificing the advantages thereof, including both those advantages herein 120 specifically pointed out or suggested and also those other advantages which will be discernible to those skilled in the art.

125 Therefore it will be understood that the disclosure herein is illustrative only, and that my invention is not limited thereto.

I claim:

1. The method of introducing ballast to fill tightly the space beneath a track-supporting member between said member and the under-bed, which comprises: depositing ballast about said member; and then applying pressure to such ballast adjacent said member on opposite sides of said member simultaneously, on each side over a considerable area simultaneously and in a direction to force such ballast under said member and compact such ballast in said space thus to fill said space tightly with compacted ballast.

2. The method of introducing concrete ballast to fill tightly the space beneath a track-supporting member between said member and the under-bed, which comprises: depositing such concrete about said member; and then applying pressure to such concrete adjacent said member over a considerable area simultaneously and in a direction to force such concrete to flow under said member and compact such concrete in said space thus to fill said space tightly with compacted concrete.

3. The method of introducing concrete ballast to fill tightly the space beneath a track-supporting member between said member and the under-bed, which comprises: depositing such concrete about said member; and then applying generally lateral pressure to such concrete adjacent said member over a considerable area simultaneously to force such concrete to flow from beside said member into said space and compact such concrete in said space thus to fill said space tightly with compacted concrete.

4. The method of introducing concrete ballast to fill tightly the space beneath a track-supporting member between said member and the under-bed, which comprises: depositing such concrete about said member; and then applying pressure to such concrete adjacent said member on opposite sides of said member simultaneously, on each side over a considerable area simultaneously and in a direction to force such concrete to flow under said member and compact such concrete in said space thus to fill said space tightly with compacted concrete.

5. The method of introducing ballast to fill tightly the space beneath a track-supporting twin-tie bearing plate between said bearing plate and the under-bed, which comprises: depositing ballast about said bearing plate; and then applying pressure to such ballast adjacent said bearing plate over a considerable area simultaneously and in a direction to force such ballast under said bearing plate and compact such ballast in said space thus to fill said space tightly with compacted ballast.

6. The method of introducing ballast to fill tightly the space beneath a track-supporting twin-tie bearing plate between said bear-

ing plate and the under-bed, which comprises: depositing ballast about said bearing plate; and then applying pressure to such ballast adjacent said bearing plate on opposite sides of said bearing plate simultaneously, on each side over a considerable area simultaneously and in a direction to force such ballast under said bearing plate and compact such ballast in said space thus to fill said space tightly with compacted ballast.

7. The method of introducing concrete ballast to fill tightly the space beneath a track-supporting twin-tie bearing plate between said bearing plate and the under-bed, which comprises: depositing such concrete about said bearing plate; and then applying pressure to such concrete adjacent said bearing plate over a considerable area simultaneously and in a direction to force such concrete to flow under said bearing plate and compact such concrete in said space thus to fill said space tightly with compacted concrete.

8. The method of introducing concrete ballast to fill tightly the space beneath a track-supporting twin-tie bearing plate between said bearing plate and the under-bed, which comprises: depositing such concrete about said bearing plate; and then applying pressure to such concrete adjacent said bearing plate on opposite sides of said bearing plate simultaneously, on each side over a considerable area simultaneously and in a direction to force such concrete to flow under said bearing plate and compact such concrete in said space thus to fill said space tightly with compacted concrete.

9. The method of introducing ballast to fill tightly the space beneath a track-supporting twin-tie bearing plate between said bearing plate and the under-bed, which comprises: depositing ballast about said bearing plate; and then applying generally lateral pressure to such ballast adjacent said bearing plate, over a considerable area simultaneously, to force such ballast from beside said bearing plate into said space and compact such ballast in said space thus to fill said space tightly with compacted ballast.

10. The method of introducing concrete ballast to fill tightly the space beneath a track-supporting twin-tie bearing plate between said bearing plate and the under-bed, which comprises: depositing such concrete about said bearing plate; and then applying generally lateral pressure to such concrete adjacent said bearing plate, over a considerable area simultaneously, to force such concrete to flow from beside said bearing plate into said space and compact such concrete in said space thus to fill said space tightly with compacted concrete.

11. A machine for introducing ballast deposited about a track-supporting twin-tie into the space beneath a bearing plate of said twin-tie and between said bearing plate and

the under-bed, to fill said space tightly with such ballast well-compacted, comprising: a car; a pair of heads, each of large area and adapted to contact such ballast simultaneously over a large area, supported from said car to contact such ballast on both sides of said bearing plate; and head operating means carried by said car for applying said heads to such ballast adjacent said bearing plate on opposite sides of said bearing plate and then simultaneously moving said heads against such ballast in directions to force such ballast under said bearing plate simultaneously from opposite sides of said bearing plate, and to compact such ballast beneath said bearing plate between said bearing plate and such under-bed.

12. A machine for introducing ballast deposited about a track-supporting twin-tie into the spaces beneath the bearing plates of said twin-tie and between said bearing plates and the under-bed, to fill said spaces tightly with such ballast well-compacted, comprising: a car; two pairs of heads, each head of large area and adapted to contact such ballast simultaneously over a large area, said pairs of heads supported from said car to contact such ballast on both sides of said bearing plates, each pair to contact such ballast on both sides of the corresponding said bearing plate; and head operating means carried by said car for applying each pair of said heads to such ballast adjacent the corresponding said bearing plate on opposite sides of said bearing plate and then moving said heads against such ballast in directions to force such ballast under said bearing plate from opposite sides of said bearing plate, said head operating means moving each pair of heads against such ballast simultaneously thus to force such ballast under the corresponding said bearing plate simultaneously from opposite sides of said bearing plate, and to compact such ballast beneath said bearing plate between said bearing plate and such under-bed.

13. A machine for introducing concrete ballast deposited about a track-supporting twin-tie into the space beneath a bearing plate of said twin-tie and between said bearing plate and the under-bed, to fill said space tightly with such concrete well-compacted, comprising: a car; a pair of heads, each of large area and adapted to contact such concrete simultaneously over a large area, supported from said car to contact such concrete on both sides of said bearing plate; and head operating means carried by said car for applying said heads to such concrete adjacent said bearing plate on opposite sides of said bearing plate and then simultaneously moving said heads against such concrete in directions to force such concrete to flow under said bearing plate simultaneously from opposite sides of said bearing plate and to

compact such concrete beneath said bearing plate between said bearing plate and such under-bed.

14. A machine for introducing ballast deposited about a track-supporting twin-tie into the space beneath a bearing plate of said twin-tie and between said bearing plate and the under-bed, to fill said space tightly with such ballast well-compacted, comprising: a car running on the track being ballasted; a pair of heads, each of large area and adapted to contact such ballast simultaneously over a large area, supported from said car to contact such ballast on both sides of said bearing plate; and head operating means carried by said car for applying said heads to such ballast adjacent said bearing plate on opposite sides of said bearing plate and then simultaneously moving said heads against such ballast in directions to force such ballast under said bearing plate simultaneously from opposite sides of said bearing plate and to compact such ballast beneath said bearing plate between said bearing plate and such under-bed.

15. A machine for introducing ballast deposited about a track-supporting twin-tie into the spaces beneath the bearing plates of said twin-tie and between said bearing plates and the under-bed, to fill said spaces tightly with such ballast well-compacted, comprising: a car running on the track being ballasted; two pairs of heads, each head of large area and adapted to contact such ballast simultaneously over a large area, said pairs of heads supported from said car to contact such ballast on both sides of said bearing plates, each pair to contact such ballast on both sides of the corresponding said bearing plate; and head operating means carried by said car for applying each pair of said heads to such ballast adjacent the corresponding said bearing plate on opposite sides of said bearing plate and then moving said heads against such ballast in directions to force such ballast under said bearing plate from opposite sides of said bearing plate, said head operating means moving each pair of heads against such ballast simultaneously thus to force such ballast under the corresponding said bearing plate simultaneously from opposite sides of said bearing plate, and to compact such ballast beneath said bearing plate between said bearing plate and such under-bed.

16. A machine for introducing ballast deposited about a track-supporting twin-tie into the space beneath a bearing plate of said twin-tie and between said bearing plate and the under-bed, to fill said space tightly with such ballast well-compacted, comprising: a car; a pair of heads, each of large area and adapted to contact such ballast simultaneously over a large area, supported from said car to contact such ballast on both sides of said bearing plate; and head operating means car-

ried by said car for imparting to said heads a movement applying said heads to such ballast adjacent said bearing plate on opposite sides of said bearing plate and then simultaneously moving said heads against such ballast in directions to force such ballast under said bearing plate simultaneously from opposite sides of said bearing plate, and to compact such ballast beneath said bearing plate between said bearing plate and the under-bed.

17. A machine for introducing concrete ballast deposited about a track-supporting twin-tie into the space beneath a bearing plate of said twin-tie and between said bearing plate and the under-bed, to fill said space tightly with such concrete well-compacted, comprising: a car; a pair of heads, each of large area and adapted to contact such concrete simultaneously over a large area, supported from said car to contact such concrete on both sides of said bearing plate; and head operating means carried by said car for imparting to said heads a movement applying said heads to such concrete adjacent said bearing plate on opposite sides of said bearing plate and then simultaneously moving said heads against such concrete in directions to force such concrete to flow under said bearing plate simultaneously from opposite sides of said bearing plate, and to compact such concrete beneath said bearing plate between said bearing plate and the under-bed.

18. A machine for introducing ballast deposited about a track-supporting twin-tie into the space beneath a bearing plate of said twin-tie and between said bearing plate and the under-bed, to fill said space tightly with such ballast well-compacted, comprising: a car; a pair of heads, each of large area and adapted to contact such ballast simultaneously over a large area, supported from said car to contact such ballast on both sides of said bearing plate; and head operating means carried by said car for imparting to said heads a generally lateral movement applying said heads to such ballast adjacent said bearing plate on opposite sides of said bearing plate and then simultaneously moving said heads against such ballast in directions to force such ballast under said bearing plate simultaneously from opposite sides of said bearing plate, and to compact such ballast beneath said bearing plate between said bearing plate and the under-bed.

19. A machine for introducing concrete ballast deposited about a track-supporting twin-tie into the space beneath a bearing plate of said twin-tie and between said bearing plate and the under-bed, to fill said space tightly with such concrete well-compacted, comprising: a car; a pair of heads, each of large area and adapted to contact such concrete simultaneously over a large area, supported from said car to contact such concrete

on both sides of said bearing plate; and head operating means carried by said car for imparting to said heads a generally lateral movement applying said heads to such concrete adjacent said bearing plate on opposite sides of said bearing plate and then simultaneously moving said heads against such concrete in directions to force such concrete to flow under said bearing plate simultaneously from opposite sides of said bearing plate, and to compact such concrete beneath said bearing plate between said bearing plate and the under-bed.

20. A machine for introducing ballast deposited about a track-supporting twin-tie into the space beneath a bearing plate of said twin-tie and between said bearing plate and the under-bed, to fill said space tightly with such ballast well-compacted, comprising: a car; a pair of heads, each of large area and adapted to contact such ballast simultaneously over a large area, supported from said car to contact such ballast on both sides of said bearing plate; and head operating means carried by said car for imparting to said heads a generally lateral straight-line movement applying said heads to such ballast adjacent said bearing plate on opposite sides of said bearing plate and then simultaneously moving said heads against such ballast in directions to force such ballast under said bearing plate simultaneously from opposite sides of said bearing plate, and to compact such ballast beneath said bearing plate between said bearing plate and the under-bed.

21. A machine for introducing concrete ballast deposited about a track-supporting twin-tie into the space beneath a bearing plate of said twin-tie and between said bearing plate and the under-bed, to fill said space tightly with such concrete well-compacted, comprising: a car; a pair of heads, each of large area and adapted to contact such concrete simultaneously over a large area, supported from said car to contact such concrete on both sides of said bearing plate; and head operating means carried by said car for imparting to said heads a generally lateral straight-line movement applying said heads to such concrete adjacent said bearing plate on opposite sides of said bearing plate and then simultaneously moving said heads against such concrete in directions to force such concrete to flow under said bearing plate simultaneously from opposite sides of said bearing plate, and to compact such concrete beneath said bearing plate between said bearing plate and the under-bed.

In testimony whereof I hereunto affix my signature.

THOMAS J. LAVAN.
